TOBIAS S. KREIDER, OF BIRD IN HAND, PENNSYLVANIA.

DESIGN FOR AN ARTICLE OF MANUFACTURE.

52,993.

Specification for Design.

Patented Feb. 11, 1919.

Application filed December 3, 1917. Serial No. 205,265. Term of patent 14 years.

To all whom it may concern:

Be it known that I, TOBIAS S. KREIDER, a citizen of the United States of America, residing at Bird in Hand, in the county of Lancaster and State of Pennsylvania, have invented a new, original, and ornamental Design for an Article of Manufacture, of which the following is a specification, reference being had to the accompanying drawing, forming part thereof.

In the drawing I have shown a represen-

tation of a glass bowl embodying my design.

The design as shown comprises oval figures arranged seemingly haphazard upon a glass bowl having a bulged form, but I contemplate that the same may be applied to transparent receptacles of similar shapes.

I claim:

The ornamental design for an article of manufacture, as shown and described.

TOBIAS S. KREIDER. [L. S.]
